MECHANICAL CEMENT TROWEL OR
FLOATER

Stanley W. Marsh, Valley Falls, Kans.

Application November 14, 1950, Serial No. 195,546

2 Claims. (Cl. 94—45)

1

This invention relates to masonry and concrete implements, and more particularly to a mechanical cement trowel or floater.

An object of this invention is to provide a cement trowel of the type including an oscillatory plate which is particularly adapted to float and finish cement work.

Another object of this invention is to provide a cement trowel which is electrically actuated and is particularly adapted for easy maneuverability by an operator.

A further object of this invention is to provide a mechanical cement trowel or floater which is relatively simple in structure and cheap to manufacture.

A still further object of this invention is to provide a mechanical cement trowel or floater which is light and compact in structure to thereby particularly adapt the trowel for easy portability.

The above and still further objects and advantages of the present invention will become apparent upon considering the following detail description of the invention, when taken in conjunction with the accompanying drawings, wherein:

Figure 1 is a top plan view of the mechanical cement trowel of the present invention;

Figure 2 is a sectional view taken substantially along the line 2—2 of Figure 1;

Figure 3 is an end elevational view taken from the left of Figure 1.

Referring now more particularly to the drawings, wherein like reference numerals have been used throughout the several views to designate like parts, there is shown the mechanical cement trowel of the present invention, generally designated by the reference numeral 10 which includes a base plate 11 and a work engaging plate 12 disposed in spaced parallel and confronting relation with respect to the base plate.

Extending between the base plate 11 and the work engaging plate are the resilient elements generally designated by the reference numeral 13 which are secured between the base and work engaging plates.

Operatively connected to the work engaging plate is the electrically actuated motive means 14 which includes an electric motor 15 and an offset or driven shaft 16 for effecting the oscillatory movement of the work engaging plate 12 in a plane substantially parallel to the plane of the base plate. The motive means 14 embodies the offset shaft 16 which has its long axis disposed transversely of the plates 11, 12 in per-

pendicular relation to said planes of the plates and has one end projecting through an aperture 17 provided in the base plate 11 and has the other end terminating contiguous to the inner face 18 of the work engaging plate 12. Carried by the outer face 19 of the base plate 11 is a bearing 20 which rotatably journals the adjacent end of the offset shaft. Carried by the inner face 18 of the work engaging plate 12 is a second bearing 21 which rotatably journals the stub shaft 22 carried by the offset shaft 16, and having its axis offset from said axis of the shaft 16, for movement of the stub shaft through a circular path about the axis of the shaft 16. It is to be noted that there is clearance between the inner race 23 of the bearing 21 and the stub shaft 22 to thereby loosely rotatably journal the adjacent end of the offset shaft 16 to permit the desired oscillatory movement of the work engaging plate 12 with respect to the base plate 11. The electric motor is spaced above the outer face 19 of the base plate 11 and is supported by means of the bracket 25 which is carried by the base plate 11 and bolted to the base 26 of the motor 15 by means of the bolts 27, 28. The motor 15 includes a power shaft 29 which projects through a longitudinally extending slot 30 provided in the base plate 11, the power shaft being arranged in spaced parallel relation with respect to the offset shaft 16.

Disposed intermediate the base and work engaging plates 11, 12 is a pulley 31 which is circumposed about the offset shaft and secured transversely thereof in a plane paralleling the planes of the plates. Arranged in coplanar relation with respect to the pulley 31 is a pulley 32 which is carried by the adjacent end of the power shaft 29. An endless belt 33 is trained about the pulleys 31, 32 and couples the power shaft 29 of the motor 15 to the offset shaft 16. Accordingly upon actuation of the motor, the offset shaft 16 will impart the desired oscillatory movement to the work engaging plate 12 to thereby float and finish the cement being worked.

Carried on the outer face of the base plate 11 contiguous to each side edge thereof are the opposed L-shaped hand grips 34, 35 which permit the cement trowel to be manually grasped by an operator to move the work engaging face 12 into engagement with the cement work to be floated and finished.

As clearly shown in Figure 3, the hand grips 34, 35 are each pivotally mounted for rotary movement about an axis at right angles to the base plate 11. The hand grip 34 is pivoted by the pin

36 secured thereto and journaled transversely of the base plate 11, and the hand grip 35 is pivoted by the pin 37 secured thereto and journaled transversely of the base plate 11.

Although only one embodiment of the cement trowel of the present invention has been described it is readily apparent that numerous modifications can be made without departing from the spirit of the invention set forth in the appended claims.

What I claim is:

1. A cement trowel comprising a base plate and a work engaging plate arranged in spaced parallel planes, resilient means extending between said base and work engaging plates respectively, and electrically actuated motive means operatively connected to said work engaging plate for effecting the oscillatory movement of the latter in a plane substantially parallel to said base plate, said motive means including a driven shaft having its long axis perpendicular to the planes of said plates and having one end rotatably journaled on said base plate, a stub shaft extending from the other end of and having its axis offset from said axis of the driven shaft, for movement of the stub shaft through a circular path about said axis of the driven shaft, said stub shaft being rotatably journaled on said work engaging plate, an electric motor arranged outwardly of said base plate and secured to the latter, said motor including a power shaft arranged in spaced parallel relation with respect to said driven shaft and projecting into the space between said plates, and coupling means operatively connecting said power shaft to said driven shaft.

2. A cement trowel comprising a base plate and a work engaging plate arranged in spaced parallel planes, resilient means extending between said base and work engaging plates respectively, and

electrically actuated motive means operatively connected to said work engaging plate for effecting the oscillatory movement of the latter in a plane substantially parallel to said base plate, 5 said motive means including a driven shaft having its long axis perpendicular to the planes of said plates and having one end rotatably journaled on said base plate, a stub shaft extending from the other end of and having its axis offset from said axis of the driven shaft, for movement of the stub shaft through a circular path about said axis of the driven shaft, said stub shaft being rotatably journaled on said work engaging plate, an electric motor arranged outwardly of 10 said base plate and secured to the latter, said motor including a power shaft arranged in spaced parallel relation with respect to said driven shaft and projecting into the space between said plates, and coupling means operatively connecting said power shaft to said driven shaft, 15 said coupling means comprising a first pulley circumscribed about said driven shaft and secured transversely thereof to rotate in a plane paralleling said planes of the plate, a second pulley arranged in coplanar relation with respect to said first pulley and carried by said power shaft, and 20 an endless belt trained about said pulleys.
